DUCK NOSE AIRCRAFT OR THE LIKE

Mike Tecton, 5101 45th St. NW,
Washington, D.C. 20016

Filed Sept. 3, 1965, Ser. No. 86,839

Term of patent 14 years

(Cl. D71—1)

FIG. 5

FIG. 1 is a perspective view of a duck nose aircraft or the like, embodying my new design;

FIG. 2 is a side elevational view thereof;

FIG. 3 is a rear elevational view thereof;

FIG. 4 is a top plan view of the front nose section thereof;

FIG. 5 is a reflected underside view thereof;

FIG. 6 is a cross section view showing the general configuration along line 6—6 in FIG. 5 thereof;

FIG. 7 is a cross section view showing the general configuration along line 7—7 in FIG. 5 thereof;

FIG. 8 is a cross section view showing the general configuration along line 8—8 in FIG. 5 thereof.

I claim:

The ornamental design for a duck nose aircraft or the like, substantially as shown and described.
